[57] **ABSTRACT**

A method of production of a zip fastener by weaving, whereby within the range of the weaving station for the formation of the series of coupling members a continuous profile tape of synthetic material is turned around about a mandrel forming a loop and is bound up in the tape web, which comprises the steps of guiding back and forth the member-forming profile tape as a warp thread shed forming through the web plane, feeding thereby in a cycle continuously the profile cord about said loop-forming mandrel and binding it up by at least one weft thread.

**METHOD AND APPARATUS FOR PRODUCTION
OF A ZIPPER BY WEAVING**

The present invention relates at first to a method of production of a slide fastener by weaving, whereby within the range of the weaving station for the formation of a series of link elements a continuous profile tape of synthetic material is bent over about a loop-forming mandrel and is tied off in the woven tape. Furthermore, the present invention relates to an apparatus for the production of a slide fastener within the context of a weaving process with a series of link elements formed from a continuous sectional strand, in which series of link elements a loop-forming mandrel is provided within the range of the weaving station.

In a known method helical spring-like coils are formed in a sectional strand of synthetic material around a loop-forming mandrel such, that the sectional strand plastic material is wound to and fro as a weft thread and thereby tying it on to the warp threads of the slide fastener woven simultaneously thereby. By this arrangement in addition to one weft thread for weaving the carrier tape, a particular weft thread required in the form of a sectional strand of plastic material is required for the formation of the series of link elements. Such durable-weft weaving process permits only very slow working speeds.

In another known weaving process, which is performed without a loop-forming mandrel, prefabricated rows of link elements are used, which are tied on merely at the weaving point by the weft to the carrier tape. The formation of the row of link elements and the subsequent weaving of the carrier tape and the tying of this row of link elements are separate operations. Of a disadvantage is thereby that the rows of link elements can only be produced in additional time-consuming operations.

Difficulties are encountered, however, in particular in tying the prefabricated rows of link elements later without difficulty during subsequent weaving to the carrier tape, since it is decisive, to position each of the tie threads into the correct gaps between the turns of the coil forming the row of link elements during the weaving. One uses, for this reason, complicated additional devices on the loom in form of protective tubes covering the rows of elements and the function of which is to direct the tie thread only at the weaving point into the row of elements. Sometimes one uses still additional retaining fingers, which close up the gap between the turns of the coil upon insertion of the tie thread into the rows of link elements.

It is one object of the present invention to provide a method of and an apparatus for the production of a slide fastener by weaving wherein the row of elements are tied directly during weaving of the sectional strand of plastic material exactly and in a possibly simple and fast manner and is immediately tied on to the carrier tape.

It is another object of the present invention to provide a method of and an apparatus for production of a slide fastener by weaving, wherein the sectional strand is fed back and forth as a warp thread and thereby is tied in rhythm with this movement progressively around a loop-forming mandrel and tying it off by means of a weft thread.

The sectional strand of plastic material, now operating as a warp thread permits very high working speeds

during the weaving operation of the entire slide fastener. The sectional strand is placed in a thread supply container of any selectively large storage capacity, so that an interruption of the weaving operation due to emptying of the container is no longer likely to arise in practice. Furthermore, no additional measures are required in order on the one hand to obtain an exact shape in the rows of link elements and on the other hand properly tying of each of the link elements by the weft thread at the desired point along the woven carrier tape. By passing the sectional strand around about the loop-forming mandrel, the cross-section of the coil of the strand for forming the individual link elements is exactly secured, whereby this formation takes place directly on the weaving station, shortly before it is fixed by tying off by means of at least one weft thread. Thereby is the tie-off point of the weft thread exactly predetermined at each point where the sectional strand is passed around the loop-forming mandrel, whereby no particular measures are required, in order to locate the weft thread in the gap between turns constituting adjacent link elements occurring at the weaving point. By the distance between the wefts and by the pull-off action in the woven material the desired pitch of the turns forming the row of link elements can be produced in a simple manner. After the weaving, the row of link elements is already secured in the required coiled form without requiring further operations. Also the weaving process is disposed very simply, since a simple one-ply weave thus a single weaving plane suffices in order to produce the row of link elements and for the tying off to be accomplished in a proper manner.

The shed-forming movement of the sectional strand takes place by the strands being wound upwardly and downwardly, through the plane of weave, this plane being fixed by the line along which picking takes place and the beat-up line of the reed. The warp thread forming the link elements can be passed through by means of known thread guides through this plane of weave to perform its shed-forming movement, whereby these thread guides can spread the linking elements forming warp thread for the passage of the weft thread into a top shed or a bottom shed or a top-bottom shed. Suitably, one gives to the link members forming warp thread a greater shed-forming movement in comparison with the warp threads forming part of the woven fabric.

In order to improve the passing of the warp thread, forming the link elements, the loop-forming mandrel, it is advisable intermittently to deflect this thread laterally in relation to the plane of the heald, in addition to imparting the shed-forming movement to it. This could be obtained by a lateral component in the movement of the corresponding thread guide for the shed-forming movement of warp thread constituting the link elements, however, but also by means of guide surfaces disposed within the path of the stroke lifting movement could give to the movement of warp thread the desired transverse component for passing this thread around the loop-forming mandrel.

It is advisable to retain, during the stroke of the warp threads forming the tape of the slide fastener of the free-fixing end of the loop-forming mandrel always on the same side of the weave plane, so that the mandrel is always engaged either at its bottom or at the top by the weft thread, but cannot alternatively bear against the weft thread first from the top and then from under-

neath. The simplest possibility resides in the fact, that the fixing end of the loop-forming mandrel is provided static. In order to simplify the winding around movement of the member-forming warp thread around the loop-forming mandrel, one can impart to the fixing end of the mandrel a movement, which is opposite to the above-mentioned movement of the warp thread, constituting the slide elements however, even here without crossing the plane of weave. The non-fixed end of the loop-forming mandrel is disposed thus in one of the two web-shed part ranges or grooves, namely either above the plane of weave or below the plane of weave, so that the warp thread forming the link elements is passed around in one of the two web-shaped part ranges or grooves about the member forming warp thread. For reasons of simplification of the operation, the warp thread forming the link members performs its weave stroke movements always on the side pointing toward the carrier tape part of the loop-forming mandrel and is brought only for a short time period during moving around the loop-forming web to the opposite side.

The winding about of the member forming warp thread around the mandrel can take place each time, in accordance with the distance between two consecutive link elements when this warp thread enters the shed where the non-fixed end of the loop-forming mandrel is disposed. This could take place at each second picking action, which leads to slide fasteners of light weight qualities. For heavier qualities it is advisable to wind the warp thread forming the link elements around between successive entrance loops a plurality of picking movements around the warp thread forming the link elements, whereby with constant pull-off action on the fabric a greater distance between the successively formed linking elements is created. To tie in or cover the elements in a firmer manner of the members, it is desirable to tie off additional warp threads in the known manner near the rear portions of the turns constituting the warp members that form the link elements.

To increase the firmness of the engagement of the weft threads, it is advisable further to deform the cross-section of the warp thread, constituting the link members, prior to reaching the weaving point. These deformed portions can also be used for the purpose of predetermining positions at which links are formed at the weaving point for the subsequent forming of the turns of the coil. These deformed portions of the cross-section could be used for the complementary forming of linking faces on the individual linking elements, and the depth of engagement of the link elements in the row of elements of the complementary half of the slide fastener can also be determined by deformed portions in the cross-section that act as stops. In order to facilitate the passing around of the warp thread forming the link elements around the mandrel, it is of advantage to feed this warp thread to the weaving point in predetermined lengths. Expediently, the feed means is combined with above-mentioned device, so that the rate of feed is precisely matched to the successions of deformed portions in the cross-section, and these two stops are also carried out in rhythm with the weaving process.

The present invention is also directed towards equipment for manufacturing of the initially-mentioned slide fastener. This equipment is characterized in that the loop-forming mandrel is accommodated in a holder containing a hole through which the warp thread, forming the link members, passes is guided in a thread guide

actuated in rhythm in the weaving process. To form a loop, the warp thread constituting the link members is passed through the opening in the mandrel holding means, so that, after passing completely around of the mandrel end, mounted in the holding means, it returns to its original position. In doing this, the warp thread will have circled the mandrel in the mandrel holder. The fixing end of the loop-forming mandrel is arranged between the guide means for the warp threads and the tie-off point where the weft is picked and beaten up.

In the simplest sense the warp thread forming the link elements is passed through the opening solely by the guide means that cause its weave-lift movement. The mandrel holder and the opening therein can be of various forms, each of which has a special advantage.

One possible way is for the mandrel holder to be constituted by a bearing bush and an insert which accommodates the loop-forming mandrel in the bush, there being a radial gap between the bush and the insert and this gap alone constituting the opening through which the warp thread, forming the link elements, passes. In a practical arrangement, the insert could consist of a sphere, in which is let the end of the mandrel and which is surrounded by a dished member, there being a radial gap between said member and the sphere, so that the warp thread constituting the link elements can pass through the gap between the sphere and the dished member. Instead of providing a radial gap between insert and the bearing, it would also be possible to support the insert on fingers that extend towards each other in the radial direction, the opening for the warp thread in this case being created by lifting the fingers in succession from the points where they bear on the insert and thus periodically creating an opening, through which the warp thread forming the link elements can be guided.

It is however particularly advantageous to provide in the bearing a rotatable member which accommodates the fixing end of the loop-forming mandrel, and which has an off-center opening for the warp thread forming the link elements. This warp thread passes through a slot in the bearing into this off-center opening in the rotatable member, by which the warp thread is passed around the loop-forming mandrel, when the rotatable member rotates. In the simplest case, this rotary movement of the rotatable member is produced by entry movement of the warp thread itself, since the rotating member takes the form of a gyrating mass. In order to limit if necessary, the movement of the rotatable member in its bearing and to control the commencement and the end of the rotary movement in a precise manner, it is of advantage to provide on the rotatable member a means for blocking this rotary movement, e.g., in the form of a pawl or a catch, which can be rendered operative and inoperative as required.

Finally, however, it is also possible to connect the rotatable member to a drive actuable in rhythm with the weaving process, this drive imparting a forced movement whereby the warp thread forming the link elements is also passed round the loop-forming mandrel independently of its own normal movement.

Since the winding of the warp thread forming the link elements around the loop-forming mandrel is first carried out near the mandrel holder which, as already mentioned, is arranged between the thread guide means, on the one hand, and the tie-off point on the other, is thus located at a distance from the tie-off

point. It is of importance, that the loop produced should be allowed to run to the tie-off point. For this purpose, it is advantageous for the loop-forming mandrel not to extend rectilinearly from its anchored portion, but for it to be deflected. This deflection can be from the horizontal weaving plane or relative to the longitudinal direction of the warp thread, but expediently the deflection is effected in relation to both of these reference factors. In the simplest case deflection is achieved by imparting a permanent bend to the loop-forming mandrel near its fixing end.

With these and other objects in view, which will become apparent in the following detailed description, the present invention, which is shown by example only, will be clearly understood in connection with the accompanying drawings, in which:

FIG. 1 is a side elevation of the part most important for the understanding of the present invention of a weaving device in a schematic showing;

FIG. 2a, as well as FIG. 3a, are slightly enlarged side elevations of the loom within the range of the tie-in point in two different working positions;

FIGS. 2b and 3b are corresponding top plan views of the fabric and the individual threads creating the latter within the range near the tie-in point for the two previously-mentioned working positions;

FIG. 4 is a cross-section through a component of the loom designed in accordance with the present invention, with a working path followed by the warp thread that forms the link elements; and

FIG. 5 is a longitudinal section through the components in FIG. 4 along the section lines V — V of FIG. 4.

Referring now to the drawings, in manufacturing a slide fastener strip 10, a continuously woven-in weft thread 12, in addition to the required number of warp threads 11, is used for producing the carrier tape portion 25. For the forming a row of link elements 14, one is made of a warp-thread 15 from which the elements are formed and which consists of an initially extended strand of plastics material. Near the tie-in point, this strand is passed round a loop-forming mandrel 16, in the manner to be described below, for the purpose of forming helical turns.

In the present case, a pick inserting needle 17, which can be seen in cross-section in FIG. 1, is used as a means for inserting the weft thread 12. With the aid of this needle, the weft thread 12, as shown in FIGS. 2a to 3b, is inserted in the shed as a loop 34 comprising a doubled thread portion. The warp threads 11 for the tape, as well as the warp thread 15 also referred to as a sectional warp strand or a profile warp strand, constituting the link elements, are spread apart to form a shed 18 to enable the weft thread to pass through.

The warp threads 11 forming the tape are moved alternately into a top shed 19 and a bottom shed 20, the movements being relative to the plane of weave WE which is defined by the line of movement of the pick-inserting needle 17 and the beat-up point of the reed 30 and is indicated in FIGS. 1, 2a and 3a by a dash-and-dot line, while at the same time, the warp thread 15 constituting the link elements is selectively located either in the top shed 19' as in FIG. 2a, or in the bottom shed 20' as in FIG. 3a.

In the present case, normal healds 21, 22 and 23 are used as thread guide means for forming the shed 18. The number of healds will depend upon the type of fab-

ric binding required. The rods for moving the healds, and the heald control means are of the usual design and are therefore not illustrated.

Depending upon the required weave pattern, the various warp threads 11 are drawn into the healds 24 of the healds, which in the present case are represented by the two healds 22 and 23. The warp thread 15 forming the link elements is drawn in a further heald 21.

In the present case the holder 32 is rigidly secured to 10 a carrier 46 of the loom. The outer part of this holder 32, namely a bearing bush 38 later still to be described, carries a flange 48 on one side (FIG. 4) which is secured by several screws 47 on a carrier 46, the holder 32 is thereby secured in a position, with which it projects into the movement path of the member-forming warp thread 15, if the latter performs the spreading movement to be discussed later closely in connection with FIG. 4 based on the to and fro movement of its shaft 21. The warp thread reaches thereby the two extreme positions 15' and 15'' shown in FIG. 4.

The warp threads 11 of the tape are drawn from a thread supply container (not shown) and are guided round a warp thread reversing rod 26 to the healds 22 and 23.

The container for supplying the warp threads 15 forming the link elements is not shown either. Also the container for supplying the warp threads 15 is not shown. This warp thread is guided over a reversing roller 27 and passed through a feed device 28 which advances the thread in a stepwise manner in rhythm with the weaving process. The feed device consists of two rollers, the drive for which is not particularly shown, because of conventional nature. During the weaving process, the healds 21, 22 and 23 execute an up and down movement 29 in the directions indicated by the double-headed arrow shown in FIG. 1. Located in front of the healds is the beat-up reed 30 through which the warp threads 11 are drawn and which performs the function of beating up the weft thread 12 after each pick-inserting action on the already formed piece of fabric.

The loop forming mandrel 16 is permanently located above the plane of weave WE and near the warp threads located in the top shed 19, and 19'. The loop-forming mandrel 16 does not participate in the up and down movement of the warp threads and therefore does not alter its position in relation to the plane of weave WE. The rear fixing end of the mandrel is mounted in a holder disposed between the beat-up reed 30 and the healds 21. The fixed means used in the present case for attaching the holder 32 to a carrier on the loom is not particularly shown. FIGS. 1, 2a, and 3a show that the loop-forming mandrel 16 comprises a bend at the beat-up point of the reed 30 and downwards from this bend of the mandrel extends over a distance into the fabric before terminating at its run-off end 33 as shown in FIG. 1 of the drawings.

FIGS. 1, 2b and 3b show that the loop-forming mandrel 16 is deflected relatively to both the plane of weave WE and the direction 11 in which the warp threads run.

Two successive working positions are shown in the drawings to explain in more detail the process of weaving the slide fastener strip in accordance with the present invention. A plan view and a side view are shown side-by-side for each working position.

In that stage of the process shown in FIGS. 2a and 2b, the warp thread 15 forming the link elements is positioned in its top shed 19'. During the actual lifting movement of the associated heald 21, this warp thread 15 is positioned only on that side of the loop-forming mandrel 16 presented to the carrier tape portion 25. In this situation, all the other warp threads 11 for forming the tape have been spread into two groups 11' and 11'' for the formation of a bottom shed 20 and an upper shed 19, respectively.

The complete shed 18 is thus formed and the pick-inserting needle 17 whereby the weft thread 12 is inserted as the loop 34 is then passed through this shed 18. The pick-inserting needle 17 continuously passes the particular loop 34 of weft thread in the shed from the marginal zone of the fastener strip 10, which zone is provided with the later row 14 of link elements. A meshing loop 36, which is drawn through the loop created by the preceding pick-insertion action, is laid on the opposite edge of the fabric at the point 35, where the weft thread 12 is reversed, so that a row of meshes, formed from meshing loops drawn continuously, one into the other, is created at this point 35.

As can be ascertained from FIG. 2a, the warp thread 15 forming the link elements is raised during its lifting movement in the top shed 19', to a somewhat higher level than that corresponding to the top shed 19 of the warp threads 11 forming the tape and to the inclined position of the loop-forming mandrel 16. The warp thread 15 forming the link elements moves into working connection with the mandrel holder 32. The mode in which this operation takes place is explained in more detail by reference to FIGS. 4 and 5.

The holder is made in two parts and consists of a bearing disc 32, supporting the fixing end 31 of the mandrel 16 and of a bearing sleeve 38 which surrounds the disc 37, rotatable therein, and which in the present case is securely fitted to a carrier in the loom. The bearing sleeve 38 has an inlet slot 39 as can be ascertained from the cross-sectional view of FIG. 4. But also the bearing disc 37 contains an opening 40. The opening 40 and the slot 39 are arranged at first in register with the path of moving of the warp thread 15, constituting the link elements, when this thread, during its initially rectilinear lifting movement, shown in FIG. 4, executes its entry movement 41 in the direction of the arrow shown on the drawing. The warp thread 15 passes into the opening 40 before reaching the upper point of reversal of its weave lifting movement. By the incoming movement 41 of the warp thread 15, the latter strikes the inlet side 42 of the disc 37 and causes the rotation of the disc 37. The further movement of the rotating disc 37 takes place by its own inertial power. The thread is now caught in the opening 40, upon further movement of the disc 37 due to its inertia in the bearing sleeve 38. Due to the return movement of the heald 21, the warp thread 15, constituting the link elements is disposed within the range of the rotating disc for a sufficiently long time. During this time period the inertia power of the disc 37 takes the thread and moves the latter in the direction of the arrow 43 according to the point-dotted line in FIG. 4 once totally about the mandrel 16. The path of the warp thread, forming the link elements, in relation to the opening 40 is indicated in FIG. 5 by a dash-and-dot line representing the axis 15' of the thread. During this lifting movement, the thread 15 strikes the inlet side 42 of the bearing disc and sets

it in rotation in direction of the arrow 43. The bearing disc 37 is thus caused to swing and its opening 40 is turned into the bearing sleeve 38 and forms an orifice for the passage therethrough of the weft threads, constituting the link elements, between the bearing disc 37 and the bearing sleeve 38, which revolves about the loop-forming mandrel 16. While the bearing disc 37 is still rotating in the direction of the arrow 43, the downwardly directed movement of the warp thread 15, forming the link elements, is initiated by way of its heald 21 after the upper point where the movement is reversed has been passed. During this downward movement, the opening 40 will have returned to the position in which it is in register with the slot 39 in the bearing sleeve 38, so that the original position of the two components of the holder 32 is reached again. The warp thread 15, forming the link elements, now completes its outlet movement in the direction of the arrow 44, which movement is initiated by the stroke of the heald 21.

Because of the above-described circular movement of the warp thread 15, constituting the link elements, through the passage resulting from rotation in the direction of the arrow 43 in the holder 32, a further engagement loop 45 is created during the subsequent forming of the turns of the coil forming the row 14 of link elements, this loop being shown in FIGS. 3a and 3b. The bearing disc 35 rotates about an axis which, in this zone, coincides with the direction in which the loop-forming mandrel 16 extends. Accordingly, as seen in FIG. 5, the fixing end 31 of the mandrel is in turn mounted to rotate in the bearing disc 37, so that simultaneous rotation of the loop-forming mandrel 16 and the bearing disc 37 in the direction of the arrow 43 does not need to take place.

FIGS. 3a and 3b show the next stage of the method when the next loop 34' of weft thread is being inserted. In correspondence with the binding of the fabric, the distribution of the warp threads 11 in the top shed 19 and the bottom shed 20, is different from that occurring in the preceding stage of the method; other warp threads of the tape are now located in the two groups 11' and 11'' of thread forming the top shed and the bottom shed. The loop-forming mandrel 16 however is still located on the same side of the plane of weave WE; furthermore, in the present case, it has not been moved out of the position already shown in FIG. 2a. The warp thread 15, forming the slide elements, has however, moved into the bottom shed 20', which is determined by the lower reversal point between the movements 44 and 41 shown in FIG. 4. As can be seen from the loop of the weft thread 34' in FIG. 3b, the pick-inserting needle 17, now entering the opened complete shed 18, crosses over the warp thread 15, constituting the link elements and this thread, again lying between the mandrel 16 and the tape fabric 25, is thus tied on to the fabric of the carrier tape. The loop-forming mandrel 16, on the other hand, does not interact with the warp thread 15, constituting the link elements, in this stage of operation. The meshing loop 36' created on the weft thread is looped up with the preceding one, so that a further mesh is created at the edge zone. The operational cycle of the present method is thereby completed and the stage illustrated in FIGS. 2a and 2b is repeated.

The weaving process for producing a slide fastener strip, in accordance with the invention, could also comprise more than two stages. In the previously described

mode of operation, one turn 45 is formed for each second weft and thus a link element is formed. In the above-described equipment this always happens when the warp thread 15 constituting the link elements is raised into the top shed 19'. It would however be easily possible not to form a turn in each position of the top shed, but to place a turn around the mandrel 16 in the manner illustrated only each second or third time for example. All that is required for this purpose is a slide member which can be reciprocated by means of a simple control device such as an eccentric and which normally closes the slot 39 in the bearing sleeve 38 and only uncovers it when it is desired to place a turn of thread around the mandrel 16. Instead of this, it would be however possible to use a locking rod which permitted free rotation of the bearing disc only at the required moments. Finally, a gear could also be provided for the rotation of the bearing disc in the bearing sleeve, this gear being set in movement at the required moment.

Two slide fastener strips, later joined to form a complete fastener are advantageously produced alongside each other in the loom. For this purpose, the two strips are expediently woven in mirror-image fashion, side-by-side in the same loom, and with their rows of link elements facing each other. The two slide fastener strips are best joined, while still in the loom, after weaving has been completed, while they are still subjected to the pull-off tension. In this way, and if the pull-off tension is relaxed on both strips simultaneously, any irregularities in the slide fastener strips largely cancel each other out, since the two strips contract in a manner whereby they become matched up to each other. Here, it is of particular interest to use a common loop-forming mandrel for producing two associated slide fastener strips, the two warp threads, constituting the link elements, being wound round the mandrel through a common opening in synchronism with the weaving operation.

Finally, shaping rolls, which cause a change in cross-section in the warp thread 15, constituting the link elements, could be associated with the feed device 23. In this way, the turning points, facing the carrier strip portion 25, as well as the link surfaces, moving into a position on the opposite side of the mandrel, can be predetermined before the actual turns are formed. Turns having an elliptical cross-section are obtained, and this cross-section enables the shanks of the link elements, contiguous with the link faces, to extend in the forward part of the turn horizontally and to be superposed upon each other in the vertical direction, and this form of cross-section further enables the pitch of the helix to be virtually limited to the rearward portions of the turns whereby the row 14 of link elements is woven into the carrier tape. The warp threads near the warp thread 15 that constitutes the link elements are made thicker than the other warp threads so as to achieve a firmer bond, or they may be provided in a greater number so that a ridge-like thickening is imparted to the weave at this position.

While we have disclosed several embodiments of the present invention, it is to be understood that these embodiments are given by example only and not in a limiting sense.

We claim:

1. A method of manufacturing a slide fastener by weaving, in which method a sectional warp strand of plastics material is deflected about a loop-forming

mandrel within the range of a striking point of the weft of a complementary carrier tape portion for forming a row of link elements, comprising the steps of

5 passing the sectional strand to and fro through a plane of weave as a warp thread, said plane of weave being defined by a line along which picking takes place,
10 additionally passing said warp thread in a full loop around one rear end of the warp-forming mandrel, the latter being maintained on one side of the plane of weave, and
15 said sectional strand being tied off by means of a weft thread and woven into the simultaneously created carrier tape portion.

2. The method, as set forth in claim 1, which includes the steps of moving additionally intermittently said warp thread, forming said link elements, within the range of said rear end of the loop forming member across to the upward and downward movement through said weaving plane.

20 3. The method, as set forth in claim 2, which includes the step of
25 imparting deformed portions to the cross-section of said warp thread before reaching the weaving point.

4. The method, as set forth in claim 3, which includes the step of providing additional warp threads near the rear portions of said loops of said sectional strand of synthetic material.

30 5. The method, as set forth in claim 4, which includes the step of
35 performing the weaving movement of said warp thread forming the link elements by an upward and downward movement of said warp thread through said weaving plane between said loop forming mandrel and said stringer web.

6. The method, as set forth in claim 5, which includes the step of
40 executing a plurality of pick-inserting movements between consecutive loops of said warp threads laid around said loop forming mandrel forming the link elements.

45 7. The method, as set forth in claim 6, which includes the step of
50 feeding said warp thread, forming the link elements, to the weaving point in predetermined lengths.

8. An apparatus for manufacturing a slide fastener by weaving, comprising
55 a loop forming mandrel for the formation of a row of coupling members from a profile strand of synthetic material,
an upwardly and downwardly moving heald having an eye through which said profile strand extends and is carried through a shedding motion
a laterally reciprocating pick-insertion means for a weft thread for weaving a stringer web, and for weaving in a row of link elements wound about the forward end of a loop-forming mandrel,

60 the rear end of said loop forming mandrel being disposed in a holder between the movement path of said pick insertion means and the movement path of said heald, and
65 said holder including an element comprising a bearing disc carrying the rear end of said mandrel and a bearing sleeve surrounding said bearing disc, said bearing sleeve being provided with at least one passage slot aligned with the path of movement of

11

said profile strand of synthetic material and said bearing disc being provided with an opening, said slot and said opening receiving said profile strand during formation of said link elements about said mandrel.

5

12

9. The equipment, as set forth in claim 8, wherein said disc is connected to a drive actuatable in rhythm with the weaving process.
